UNITED STATES PATENT OFFICE.

NORMAN IVAN DURBRIDGE BURKE, OF AUCKLAND, NEW ZEALAND, ASSIGNOR OF
ONE-HALF TO THOMAS PHILIP SOMERVILLE, OF AUCKLAND, NEW ZEALAND.

GRAB.

Application filed January 5, 1924. Serial No. 684,644.

To all whom it may concern:

Be it known that NORMAN IVAN DURBRIDGE BURKE, subject of the King of Great Britain, residing at 11 Ethel Street, Morningside, 5 in the city of Auckland, Provincial District of Auckland, Dominion of New Zealand, has invented certain new and useful Improvements in Grabs, of which the following is a specification.

10 This invention relates to grabs used for lifting and removing loose material such as earth, gravel, coal, et cetera, or for excavating channels, berths and other areas, in harbours, rivers and the like, and has for 15 its object the provision of improvements in that type of grab which works with a single rope or chain wherein the lower pulley block is operated vertically on guides between the upper pulley block and the framework on 20 which are pivoted the jaws of the grab.

The improvements aim at the reduction of friction and the better balance of the parts which move on the guides so as to prevent the twisting of parts with a consequent jamming of the grab in action, also providing 25 for an improved trip mechanism for locking and releasing the clutches either when the load is dumped on the ground or when it is desirable to release the load whilst the grab 30 is suspended in any position off the ground.

Other novel features are means for compensating for wear on the jaws of the grab, adjusting means for opening the jaws to regulate the amount of material to be picked 35 up, encasing the lower ends of the female guides to prevent material working into the guide tubes, the insertion of rollers in the guides to reduce friction, fitting guide rollers where the rope enters the grab, in addition to means for guiding the bottom block so as to cause it to accurately align with 40 the top block, adjusting means between the bottom block and clutches, and a safety lock for holding the grab closed whilst transporting or sluing same in mid air.

In this type of grab there are provided at each side telescopic members comprising rods secured to the upper pulley block and on which slide tubes attached to the frame 45 member on which the jaws are hinged, the lower pulley block being guided up and down the said telescopic members by fixed guides in the form of sleeves to guide the lower block up and down on the telescopic

guides, the tubes of the guides being open 55 at their lower ends.

Weaknesses in this type of construction are that the guides wear and allow the telescopic members to twist and cant, causing 60 the jaws of the grab to jam tight in closing or opening, or, alternatively, causing the bottom block to jam tight on the guides in travelling up or down same.

The jamming or seizing of the working 65 parts, however, is sometimes caused by sand, shingle or other material entering the tubes at the lower end and wedging tight on the bearing surfaces inside same.

The improvements in the trip mechanism 70 in my invention consists in means for tripping the grab so as to release the load in mid air, and fixing a locking mechanism thereto so that the load cannot be accidentally discharged whilst swinging the 75 grab in mid air.

The means for compensating for wear on the jaws of the grab consist in using movable packing plates bolted to the lower edge of the top block. The adjusting means for regulating the amount of opening of the 80 jaws and consequently the amount of material picked up consists in the fixing of toggle levers at each side of the grab, the lower end of the toggle levers having holes therein, spaced at suitable intervals or equidistant, for adjusting means on to pins secured to the bucket sides, the top end being secured to the spreader arms arranged at each corner of the bucket sections, also rollers for guiding the bottom block in its vertical 85 movement, same being shaped on their periphery to correspond with the section of the vertical guides, the rollers being carried in suitable brackets attached to the sides of the bottom block.

Another improvement consists in the provision of a rope guide at the top of the upper block, the guide being made of rollers to reduce friction and undue wear on the rope, also guide plates fixed to the bottom 90 block to guide and align same positively into position against the lower edge of the upper block.

The improvements will be further described with reference to the accompanying 100 drawings wherein

Figure 1 is a side elevation of a grab with the buckets in the closed position.

Figure 2 is a similar view to Figure 1 but showing the grab open.

Figure 3 is a sectional plan of the bottom block.

5 Figure 4 is a part sectional elevation enlarged showing the mechanism for locking the lower pulley block to the frame member and to which both jaws are hinged.

10 Figure 5 is a side elevation of the top and bottom block with the trip mechanism and striking pin in position ready for discharging the load by dumping on the ground or in mid air.

15 Figure 6 is a detail of the head of the grab showing the roller guides with the rope passing through same.

Figure 7 is a detail in sectional elevation of the lower end of the telescopic members.

20 Referring to the drawing, 1 represents the upper block, 2 the lower block, 3 and 4 jaws, the latter being hinged at 5 both to the frame member 6 and the lower end of the spreader arms 11 on pins 5^a. The lower block 2 works on the telescopic 25 guides, one at each side of the grab, said guides comprising upper rod portions 7 secured at their upper ends by the top cross bars or plates and lower portions 8 shaped to work on said rods and secured at their 30 lower ends to the frame members 6. The telescopic guides can be of any desired shape in cross section and when square or circular the rollers 9 are fitted into the lower end of the rod 7 so as to minimize 35 friction and prevent jamming when the rod 7 is sliding on the lower portion, or when the lower portion 8 is sliding on the upper portion 7.

40 The rollers 9 are fitted at right angles as shown in Figure 7, two or more pairs of rollers being fitted as required throughout the length of the rod similar to those shown at the lower end of the rod in Figure 7.

45 The bottom block is guided in its movement up or down the telescopic guides by rollers 9^a having their periphery shaped as shown in Figure 3 encircling the guides, the rollers being an easy working fit on the lower portion 8 of the telescopic members, 50 an additional amount of clearance being afforded when the lower block is in its high position as shown in Figure 1 between the rollers and the rods 7, the rollers 9^a being fitted in pairs as shown in Figures 3 and 4.

55 The lower ends of the guides 8 are closed as shown at 8^a in Figure 7 so as to prevent the entrance of gravel, sand and like material into the guides, the closing being preferably effected by a screwed plug as 60 shown to facilitate cleaning or oiling.

65 The jaws 3 and 4 are geared together as in existing types by toothed sectors or other suitable means as at 10 so as to open and close together, the bucket sections being pivoted at their inner ends on the pins 5 and

at their outer ends by the hinge pins 5^a fixed at the lower ends of the spreader arms 11 on which latter the buckets fulcrum or swing during opening and closing of the grab. The extent of opening of the jaws 3 and 4 is controlled by toggle levers 12 same being hinged near the centre on pins 12^a and pivotally connected by pins 14 to the spreader arms, the extent of the opening of the jaws being varied by pivotally connecting the lower end of the levers 12 into the different holes 16 provided for connecting to the pins 15.

70 By means of these toggle levers and the adjustment provided at the lower end of same the extent of the opening of the jaws 3 and 4 can be increased or decreased as required and the quantity of material lifted and discharged varied according to requirements.

75 Provision is made to overcome undue wear on the edges of the lips 3^a and 4^a of the jaws by securing to the lower edge of the top block 1 a number of strips of metal plate 17, the grab when first used being adjusted so that when the lower block 2 is up against the strips 17, the jaws 3 and 4 will be closed with the lips 3^a and 4^a contacting with each other, Figure 1.

80 As the lips 3^a and 4^a become worn, the strips 17 are removed one by one or as required to allow the block to move further up the telescopic guides and consequently to close up the wear which has taken place on the lips 3^a and 4^a and cause same to meet.

85 The lifting rope 18, by means of which the grab is operated, runs through rollers 19, these being concaved on the periphery to encircle the rope and prevent same wearing unduly through chafing on the metal. 90 The rope is reeved through various pulleys in the top and bottom blocks according to the amount of purchase required for closing the jaws of the grab.

95 The lower block 2 may be locked to the frame member 6 by any of the well known methods in use, one form of which is shown in Figure 4 and consists of a pair of clutch members 21 pivoted at 21^a Figure 4 to the frame member 6 and connected at their inner ends by a pin 22 passing through slots 23 as shown. Clutches constructed after the manner shown by 21 are usually weighted at their outer ends 24 so that their inner slotted ends normally move upwards and cause the hooks 25 to disengage from the projections 26 at the sides of the lower edges of the bottom block 2. The latter has on its under side a central projection which serves as a striker for locking the hooks 25 over the projections 26 when the lower block strikes the clutches by means of the projection 27. The striker plate 27 is adjustable for height by means of lock nuts and bolts as shown in Figure 4. The invention, how- 100 105 110 115 120 125 130

ever, does not appertain to the system of clutching, the improvement consisting in the mechanism for locking and releasing the clutches so as to trip the load either on the ground or when suspended in mid air as required, but having a locking means to prevent the load being tripped should the grab strike or foul any obstacle whilst transporting or sluing in mid air.

10 Another improvement aimed at in the mechanism for locking and unlocking the clutches is to prevent the trigger 27^a from jamming tight due to the plate 38 sticking on the pin 39 owing to friction and also to 75 the spring 28 not operating in a direct line with the guide rod 29.

To prevent this, the spring 28 which keeps the trigger 27^a in the locked position Figures 4 and 5, is made to encircle the 20 guide rod 29. The outer end of the trigger 27^a is shaped at 30 to take, if necessary, an adjustable balance weight, the upper end 31 being turned at right angles for engaging with the striking pin above.

25 The striking pin 32 projects above the top block as shown Figures 1, 2 and 5, the rod forming the striking pin working in guides 33 and normally held up to the position shown in Figure 5 by the spring 34, 90 the lower end of which bears upon the upper surface of the guide 33 and the upper end against a collar 35 which latter is pinned or otherwise secured to the striking rod 32, the lower end of the striking pin having a

30 projection 36 as shown in Figure 5. When the head of the striking pin 32 contacts with the plate 37 the part 31 is depressed lifting the trigger 27^a clear of the clutches 21 so as to dump the load in mid air.

40 Previous to the projection 36 making contact with 31 the lower end of the rod 32 depresses the arm 48, causing the foot of 44 to swing to the right clear of the locking rod 43.

45 It is important both in the case of the guide rod 29 and the striking pin 32 that the spring operates directly in the line of action of the rod. The lower end of the guide rod 29 has a projecting plate 38 which projects sufficiently to strike the pin 39 fixed to the trigger 27^a. Over the pin we fit a roller 39^a to revolve easily on the pin and prevent the plate 38 sticking on same by friction.

50 55 To ensure the bottom block aligning true with the top block when in the position shown in Figure 1, we fix two projecting guide plates 40 to the inside of the bottom block as shown in Figure 4, the plates being turned inwards and upwards as shown so as to enter readily between the plates of the top block when the lower and upper surfaces of the top and bottom blocks come together. The packing strips 17 which are secured to the lower edge of the top block 1

are bolted as shown in Figure 5 to the flange by an angle iron member 41 as shown.

In use, the grab with the jaws 3 and 4 open and lower block in the position shown by Figure 1 is lowered on to the material 70 from which the load is to be removed. The rope 18 is slackened sufficient to allow the lower block 2 to slide down the telescopic guides 7 and 8 by means of friction rollers 9^a. When the adjustable projection 27 on 75 the lower block strikes the slotted inner ends of the clutch members 21, the hooks 25 are caused to engage over the projections 26, after which the tension on the spring 28, through the medium of plate 38 striking 80 the roller pin 39^a, depresses the inner end of the trigger 27^a as shown in Figures 4 and 5, locking clutches in position.

For this purpose, the spring 28 must be powerful enough to lift the outer end of 85 the trigger 27^a with the balance weight thereon. Owing to the clutches 21 co-acting through the medium of pin 22 the lower block 2 is securely locked to the frame member 6 during the lifting of the lower block 90 and the closing of the jaws on to the material to be lifted. When the block 2 contacts with the upper block, the jaws 3 and 4 are fully closed and the grab is swung to the position required to dump the load. 95

Whilst transferring the load, the trigger 27^a is prevented from releasing the clutches by the locking rod 43 bearing against the safety catch 44 which is normally held in the locked position Figure 5 by spring 45 100 which may be of any design suitable for holding the safety catch locked. In Figure 5 a spiral spring is shown, one end being anchored to the pivot pin 46 and the other bearing against the vertical member of 44. In its normal locked position the lower end of the safety catch 44 bears against a stop 47 fixed to the top frame or plate members. 105

In swinging or transporting the load in mid air the lower end of the rod 43 prevents the trigger 27^a lifting high enough to clear the hooks 25 on the clutches 21, thus keeping same locked should the grab strike an obstruction of any kind.

If it is required to dump the load in mid air, the grab is hoisted to the position shown in Figure 1 so that the head of the striking pin 32 contacts with the plate 37 which operation first depresses the arm 48 on the safety catch 44, causing same to swing clear of the locking rod 43, after which it depresses the outer end of the trigger 27^a, lifting the inner end of same clear of the hooks 25 on the clutches 21. 115

When the load is to be dumped on the ground, immediately the grab is lowered onto the material, the bottom block is run down a few inches, enough to allow the rod 43 to be pushed up and to let 27 strike the inner ends of 21, which allows the outer end 120 125 130

of the trigger 27^a, assisted by the balance weight 30, to fall by gravity, in turn allowing the clutches to release the hooks 25 from projections 26, the outer weighted ends 24 falling by gravity.

The travel on rod 43 is only about one half inch or sufficient to prevent the trigger 27^a from disengaging when the lower block is held up in contact with the top block, but the travel on rod 29 is much more. This is necessary to release 27^a when the load is to be dumped on the ground, the action of the mechanism then being as follows:

15 After the grab is lowered on to the ground, the bottom block is lowered and after same has travelled about half an inch, the locking rod 43 is pushed by its spring 49 to its highest position with the collar 50 resting against the guide 33. The bottom block 2 is then further lowered until the projection 27 strikes the inner slotted ends of clutches 21, which immediately takes the weight off the trigger 27^a, allowing same to fall down at 20 its outer end, carrying weight 30, and rise up at its inner end 27^a. After clutches 21 are disengaged, an upward pull on the rope 18 discharges the load.

If it should be required to open the grab 30 by pulling on a rope 42 fixed to the top end of trigger 27^a instead of using the overhead plate 37, the safety lock 44 would have to be removed.

To prevent undue strain being placed upon 35 the rope 18 when the striking pin 32 strikes the plate 37 the latter can be made slideable on the frame carrying the rope block instead of being rigidly fixed to same.

I claim:—

40 1. In a grab of the type operated by a single rope or chain on the block and tackle principle, an upper sheave block, a lower sheave block, a frame below the latter, a pair of gravity catches pivoted on the frame and adapted to engage the lower block for securing the frame and block together, a latch engageable with one of said catches for temporarily securing the same against movement, a roller arranged on the latch, a sliding rod mounted on the lower block and having an arm engageable with said roller for temporarily preventing the movement of the latch, a spring surrounding said rod for normally holding said arm in position to prevent the actuation of the latter, and an actuating member for the latch arranged on the upper block.

50 2. In a grab as claimed in claim 1, a projection on the latch, and an adjustable

weight arranged on the projection adapted 60 to assist in swinging the latch out of engagement with the catch with which it cooperates.

3. A grab as claimed in claim 1 in which said actuating member includes a slidable pin, a spring surrounding the pin for normally holding the same in its upper position, and a foot element at the lower end of the pin arranged to strike the latch when the pin is depressed. 70

4. In a grab as claimed in claim 1, a spring pressed pin carried by the lower block and cooperating with the latch to prevent the latter from disengaging the catch with which it cooperates, and an auxiliary latch 75 for said pin operated by said actuating member.

5. In a grab as claimed in claim 1, a sliding spring pressed pin carried by the lower block and arranged to prevent the actuation 80 of the latch, and a bell-crank-lever pivotally mounted on the upper block and having one of its arms arranged coaxially with the pin and its other arm arranged to be struck by said actuating member. 85

6. In a grab, an upper sheave block, a lower sheave block movable relatively to the upper block and adapted to contact with the latter, adjusting means between said blocks for limiting the extent of movement of the blocks toward each other, a frame beneath the lower block, latching means for connecting the frame and the lower block, jaws pivotally connected to the frame, arms pivotally connecting said jaws to the upper block, 95 and means for causing said jaws to open and close in unison.

7. A grab including an upper sheave block, a lower sheave block, extensible means connecting said blocks, a frame below the lower block, means for latching the frame to the lower block, jaws pivotally connected to the frame, arms pivotally connecting the jaws to the upper block, toggle links connecting the intermediate portion of said arms to said jaws, and means for varying the effective length of the links. 100

8. In a grab of the type described, upper and lower sheave blocks, and means for ensuring the lower block aligning with the upper block, said means consisting of guide plates secured to the inner sides of one of said blocks, projecting beyond one end of that block and having its free ends tilted toward each other, so as to engage the other block when one block is moved toward the other block. 110

NORMAN IVAN DURBRIDGE BURKE. 115
